UNITED STATES PATENT OFFICE.

LEANDER SHEPARD, OF BRUNSWICK, MAINE, ASSIGNOR OF ONE-HALF TO
RUSSELL W. EATON, OF SAME PLACE.

LUBRICATING DEVICE FOR SPINNING-MACHINES.

SPECIFICATION forming part of Letters Patent No. 597,331, dated January 11, 1898.

Application filed May 3, 1897. Serial No. 634,815. (No model.)

To all whom it may concern:

Be it known that I, LEANDER SHEPARD, of Brunswick, in the county of Cumberland and State of Maine, have invented an Improvement in Lubricating Devices for Spinning-Machines, of which the following description, in connection with the accompanying drawings, is a specification, like letters on the drawings representing like parts.

This invention has for its object to provide novel means for lubricating spindles and bolsters of spinning-machines, my invention relating more especially to means which I have devised for lubricating a plurality of spindles and bolsters through one and the same oil-supplying pipe.

In that class of spinning machinery where the spindle turns in a bolster supported on a bolster-rail, the bolster-bearing being located above the bolster-rail, it is customary to oil each bearing separately by means of an oil-can.

Figure 1, in front elevation, shows a sufficient portion of a spinning-machine of one variety with my improvement added to enable my invention to be understood, one of the bolsters and its support being shown in elevation, while the other is represented in section. Fig. 2 is a top or plan view of one of the bolsters, its support, and part of the bolster-rail. Fig. 3 is a section through the bolster and its support and lubricating apparatus in the line *x* of Fig. 2. Fig. 4 shows a different form of bolster-support with my improvement added.

Referring to Figs. 1 to 3, showing part of a roving-frame, A represents a revoluble spindle; A', a bolster-rail; B, a support connected therewith by a suitable bolt C, and B' a bolster sustained by said support, the said bolster, as best represented at the right in Fig. 1, being chambered to leave a bearing *b* in contact with the spindle. These parts are and may be of any usual or suitable kind, and in practice they may be operated in usual manner.

The bolster-support contains in its chambered portion a thin tube *e*, the lower end of which is expanded oil-tight in the bolster-

support, the upper end of the tube terminating near the lower end of the bearing *b*. The upper end of the tube *e* has attached to it in any suitable manner a piece of textile or other fabric, as *f*, which by contact with the oil in the oil-space *g* left between the said tube and the interior of the bolster will act by capillary attraction to draw the oil to the top of the tube *e*, where it will be applied to the rotating spindle and will lubricate it and its bearings in the bolster as the spindle and bolster change their relative vertical positions in operation in usual manner. The bolster-support, as shown best in Fig. 3, is bored to present an opening leading into the oil-chamber *g* referred to, and said opening receives an induction-pipe *h*, the upper end of which is herein represented as provided with a head *h'*, extended horizontally therefrom in opposite directions, the face of the head being concaved to receive within it a suitable pipe, as *m*, which may be of lead or tin or any other suitable material, the said pipe being kept seated in the concave seat of the head *h'* by means of a cap *h*², laid on the outer side of the pipe, suitable rings or collars, as *h*³, slipped on the head of the cap, acting to hold the same firmly in contact with the pipe and keep the pipe firmly seated.

After the bolster-supports have been secured in proper position upon the bolster-rail the pipe *m* is laid in the seat of the head *h'*, and with a suitable drill the operator drills a hole through the pipe, as at *n*, said hole intersecting the induction-orifice *n'*, so that when the oil is put into a suitable vessel or receptacle in communication with the pipe *m* the oil will flow through said pipe and will enter all of the induction-pipes and enter the oil-space *g*.

At the left in Fig. 1 I have shown the bolster *B* as provided with a sleeve *G*, having a disk *G'*, on which rests the lower end of the spool or bobbin, and said sleeve has connected with it a toothed gear *G*², of usual construction, the said sleeve and disk being revolved to rotate the spool or bobbin at the proper speed, and to lubricate this sleeve where it rotates on the stationary bolster *B*, I have

provided the bolster with an induction-orifice p , (represented by a dotted line in Fig. 1 and by full lines in Fig. 3,) which orifice, in communication with the oil-space g , may be provided with a small plug of felt or leather, the oil in the space g passing very slowly through the felt or leather in the said orifice p , as required. The fibrous material f may extend downwardly more or less into the oil-space g .

It is customary when oiling the parts of the particular machines shown in Figs. 1 to 3 to apply oil directly to the spindle above the top of the bolster, the oil so applied on the spindle lubricating the interior of the bolster, and some of the oil so applied runs down the outside of the bolster and oils the bobbin-carrying sleeve, which runs on the bolster. In this old plan any excess of oil (and there is most always an excess unless the greatest care is used) gets upon the base of the sleeve and in the rotation of the sleeve is thrown off centrifugally, and, meeting the roving, soils the same, or is thrown off and falls on the floor or on other parts of the machine; but in this my invention only a proper amount of oil, never an excess, is applied to the spindle and between it and the bolster, and the sleeve running on the bolster is not oiled by oil running down on the bolster above the sleeve, but said sleeve is oiled only at a point within it, between its ends, and the quantity of oil supplied to the sleeve by the felt or leather plug is only the amount required to keep the surface well oiled, the amount never being so excessive as to be thrown off the sleeve as the latter is being rotated.

Fig. 4 shows a supporting-case H , of usual construction, it being seated on a rail H' by a nut H^2 , and this supporting-case has an induction-tube H^3 provided, as described of the induction-tube h , Fig. 3, with an extension forming a head h' , which is concave to receive the oil-conveying pipe m , a cap h^2 lying on the outside of the pipe and being held in the seat of the head h' by means of suitable rings or clamps, as h^3 , before described. By means of a pipe connected with this class of spindle-supports a gang of them can be oiled simultaneously instead of oiling them separately.

This invention is not limited to the particular means shown for connecting the oil-supply pipe m with the tube having the induction-orifice, nor to the particular shape of the said tube, so long as it conveys oil to the oil-chamber in the bolster.

Having described my invention, what I claim as new, and desire to secure by Letters Patent, is—

1. A series of bolsters and their supports having induction-orifices extended therefrom, and an oil conducting or feeding pipe seated in the outer end of said induction-orifices, said pipe being perforated for the passage of oil in the said induction-orifices, com-

bined with clamping means to seat said pipe oil-tight upon or with relation to said induction-tubes, substantially as described.

2. A bolster having a bearing b at its upper end for a spindle, combined with a tube located within said bolster and connected oil-tight with the lower end thereof, said tube being extended upwardly within said bolster and terminating below the lower end of said bearing, leaving an oil-space between the external wall of said tube and the internal wall of said bolster, said bolster being provided with an induction-orifice to lead oil through it and into the space between itself and the said tube to operate, substantially as described.

3. A bolster provided with a tube located within it and connected oil-tight with the lower end of said bolster, said tube being extended upwardly within said bolster, leaving an oil-space between its external wall and the internal wall of the bolster, and fibrous material located in said oil-space to conduct the oil by capillary attraction to the top of said tube, substantially as described.

4. A plurality of bolster-supports and connected bolsters, a tube contained within each of said bolsters and joined oil-tight at its lower end with the bolster, the tube being of smaller diameter externally than the interior of the bolster to leave an oil-space, each of said bolster-supports having an induction-tube combined with an oil-conducting pipe seated in or connected with said oil-induction tubes, to simultaneously oil a series of said bolster-supports and bolsters and spindles running therein, substantially as described.

5. A bolster provided with a tube located within it to leave an oil-chamber between the said tube and the said bolster, and having an oil-delivery opening provided with an oil-conducting plug combined with a sleeve applied to the exterior of and rotatable on said bolster, the said plug delivering oil from the said oil-chamber between the said sleeve and bolster to lubricate the same, substantially as described.

6. A bolster provided at its interior with a tube of less diameter than the interior of the bolster to leave between said tube and bolster an oil-chamber, said bolster also having an oil-delivery opening in communication with said oil-chamber, and a piece of fibrous material as f located at the upper end of said tube and extended into said oil-chamber, combined with a spindle extended through said tube and bolster, and a revoluble sleeve surrounding said bolster outside said oil-delivery opening whereby oil in said oil-chamber is delivered not only to said spindle but also to said sleeve to lubricate both of them, substantially as described.

7. A series of bolsters and their supports having induction-orifices extended therefrom, the outer ends of said induction-orifices being provided with concaved extensions, an oil conducting or feeding pipe seated in the outer

ends of a plurality of said induction-orifices, a series of semicircular caps applied to said pipe outside of said semicircular extensions, and clamping means to unite said semicircular caps to said semicircular extensions, substantially as described.

5 In testimony whereof I have signed my

name to this specification in the presence of two subscribing witnesses.
